UNITED STATES PATENT OFFICE.

LOUIS HARTMANN, OF MOUNT VERNON, NEW YORK, ASSIGNOR TO HENRY IDEN, OF NEW YORK, N. Y.; HENRY AMREIN EXECUTOR OF SAID IDEN, DECEASED.

ACETYLENE-GAS LAMP.

1,142,421.

Specification of Letters Patent. Patented June 8, 1915.

Application filed March 20, 1912. Serial No. 685,077.

To all whom it may concern:

Be it known that I, LOUIS HARTMANN, a citizen of the United States, and resident of Mount Vernon, in the county of Westchester 5 and State of New York, have invented certain new and useful Improvements in Acetylene-Gas Lamps, of which the following is a specification.

My invention relates to acetylene gas 10 lamps of that type in which the feed is carbid to water, and it has particular relation to an improved construction of the feed portion of the plunger by which the feed is effected.

15 My improvements are especially adapted for employment in that class of lamps which comprise a composite structure for the generation and burning of acetylene gas and in which granulated or pulverulent carbid 20 is fed to a body of water in a generating chamber in successive small quantities at such frequent intervals and in such manner that the generation of gas is maintained for continuous use at the burner and the feed of 25 carbid is automatically controlled by the pressure of the gas generated.

Lamps of the structural type above set 30 forth have heretofore usually been irregular and uncertain in operation, owing to the indefinite and variable quantities of carbid fed to the generating chamber, by reason of the imperfect structural characteristics of the plunger, thus causing a fluctuating and irregular gas supply which precludes uniform 35 operation. Heretofore, the feed portion of the plunger has usually been constructed with a view to feeding the carbid in regular graduated and predetermined quantities, for instance by means of chambers formed in the 40 plunger and adapted to carry a predetermined charge of carbid, such chambers being usually arranged in successive series and being respectively of uniform capacity. Under the constructions just noted, in which 45 the desideratum is to feed the carbid in regular graduated or predetermined quantities or charges, the feed of the full charge of carbid, according to the capacity of the carbid-carrying chamber, results whether the 50 required extent of gas generation demands a lesser or greater quantity of carbid than that comprised in the charge so fed, and thereby the pressures of the generated gas fluctuate and the operation at the burner is rendered irregular and variable.

My invention is designed to overcome the conditions and objections above referred to, by providing an improved feed plunger having a feed portion adapted to feed the carbid in variable quantities which are balanced or conform to the conditions of required generation, so that there will be fed only such quantity of carbid as is required to produce the necessary generation and pressures, whereby the degree of generation is uniformly maintained and the conflux of gas 60 generating elements will be so controlled that the rate of generation will be automatically maintained in uniformity with the rate of consumption.

A further object of my invention is to provide an improved feed plunger which will be adapted for effective and positive operation under a very low gas pressure, thus enhancing the safety and convenience 70 of its use under the desirable conditions and requirements in small portable or table lamps, which is adapted to be more readily and conveniently cleaned when necessary, and which will possess advantages in point 75 of simplicity, economy in manufacture and use, effectiveness and general efficiency.

In the drawings, I have illustrated a lamp of one of the general types to which my invention especially relates, and Figure 1 is 80 a vertical sectional view of an acetylene gas lamp having my invention. Fig. 2 is a detail view, on an enlarged scale, of the lower end of the plunger in its operative relation to the valve ring, looking at the side or edge 85 of the construction constituting the feed portion of the plunger. Fig. 3 is a detail view, on an enlarged scale, of the lower end of the plunger, looking at the front or face of the construction constituting the feed 90 portion of the plunger. Fig. 4 is a detail horizontal sectional view on the line $x-x$, Fig. 2. Fig. 5 is a detail horizontal sectional view on the line $y-y$, Fig. 2. Figs. 6, 7 and 8 are detail vertical sectional views, 95 on an enlarged scale, illustrating the operative action of the feed portion of the plunger, with relation to the feed orifice constituted by the valve ring, under different 100 positions of the plunger with relation to the valve ring. Fig. 9 is a detail sectional view illustrating the gradual variations in the width of the feed orifice formed by the one-sided open recess, under the reciprocal 105 action of the plunger with relation to the 110

feed-orifice edge of the valve member. Fig. 10 is a detail sectional view corresponding to Fig. 9.

Corresponding parts in all the figures are 5 denoted by the same reference characters.

Referring to the drawings, the type of 10 lamp therein illustrated comprises a water holder, 1, which constitutes the generating chamber and base of the lamp, and the carbid holder, 2, which constitutes a chamber to which the gas passes from the generating 15 chamber. The carbid holder is arranged above the generating chamber and is provided with a convergent or inclined bottom, 3, directed toward the feed passage existing 20 between the generating chamber and the carbid holder, which inclined bottom is adapted for the downward passage of the body of carbid in the holder 2. The only communication 25 between the generating chamber and carbid holder is through said feed passage, and the carbid holder is preferably detachably mounted in connection with the generating chamber, to enable separation and convenient filling. The feed 30 passage is constituted by a flexible valve ring, 4, preferably formed of rubber and carried by a suitable holder, as at 5, which is preferably detachably connected with the bottom 35 portion of the carbid holder. The valve ring has a concentrically inclined or concave top surface, as at 6, and a concentrically inclined or concave bottom surface, as at 7, and said top and bottom surfaces converge 40 to a thin blunt inner edge, as at 8, which enhances flexibility at the feed passage and reduces the area of frictional contact with the feed plunger.

9 designates the feed plunger, which 45 reciprocally operates within the valve ring and is preferably constituted by a rod having a cylindrical contour corresponding to the feed orifice of the valve ring and frictionally bearing with relation to the inner 50 edge 8 thereof. At the top of the carbid holder is mounted a flexible diaphragm, 10, preferably formed of rubber and adapted to be expanded upwardly by the pressure of the gas which passes from the generating 55 chamber through the feed passage to the carbid holder. Means are provided for depressing said diaphragm as the gas pressure lessens, for instance a top weight, as at 11, to which the diaphragm is connected. The 60 plunger is suitably connected to said diaphragm and depends therefrom, so that its reciprocal operation is controlled by the flexible action of the diaphragm. A cover, 12, is mounted at the top of the carbid holder, over the diaphragm, and carries a suitable gas burner, 14, to which the gas is fed by a tube, 15, extending from the carbid holder. In its general detail features the 65 lamp to which my improvements are applied may be as above described or may be of any

suitable or adapted construction, the essential features of the type of lamp related to my invention being a feed passage between the generating chamber and carbid holder, a feed plunger reciprocating within said 70 passage, and a member actuated by the pressure of the generated gas to cause the actuation of the feed plunger.

In my invention and improvements, the feed plunger 9 is recessed, as at 16, at its 75 feed portion, which recess constitutes the feed portion of the plunger and is formed in the circumferential surface of the cylindrical plunger rod at one side thereof and has the conformation and operative characteristics which will be hereinafter fully described.

Beneath the recess 16 the body of the plunger circumferentially conforms to the opening or orifice in the valve ring 4, the 80 contour being preferably cylindrical, as shown at 17, whereby the feed passage is closed against the carbid when the diaphragm 10 is expanded upwardly by the gas pressure, and the same circumferential 85 contour is preferably provided immediately above the recess 16, as at 18, whereby the same closed conditions will be effected in any action of the plunger which carries the recessed carbid-feeding portion entirely beneath the feed passage.

The recess 16 is of gradually increasing 90 depth with relation to the diameter of the plunger, so that starting from the plane of the circumference of the plunger the recess gradually increases in depth and capacity, and this structural condition is best produced by a concaved reduced portion formed in the side of the plunger and constituting 95 said recess. In the preferred features of 100 construction, the recess is constituted by a concaved reduced portion having a segmental contour with relation to the longitudinal plane of the plunger, the greatest depth of said segmental concave being approximately at the central or median line of 105 the plunger, whereby at such area of greatest depth the recess is substantially the same in width as the diameter of the plunger and its width is gradually reduced as it tapers 110 in its segmental contour above and below said point of greatest depth to the periphery of the plunger. The edges of the recess 16, at said tapering portions, are preferably 115 rounded or beveled, as at 19, so that they curve and merge into the circumference of the plunger and offer no defined edge or blunt point of resistance to the passage of the carbid, whereby the action of the carbid with relation to said feed recess is facilitated.

It will be noted that the recessed construction, as comprised in my invention and improvements, forms an open recess having only one side, the single side of the recess be- 120

ing constituted by the body of the plunger at the line of the segmental curvature of the recess and the recess being entirely open at both its sides and at its front, and that the 5 one-sided open recess in its relation to the cylindrical circumferential contour of the plunger forms a feed opening with a continuous segmental or arched section and of variable width and depth, as both the width and 10 depth of the one-sided open recess gradually diminish from the point of greatest depth or the vertex of the segment (see Figs. 2 and 3). The gradual variation in the width of the feed orifice formed by the one-sided open recess, under the reciprocal action of the plunger with relation to the feed-orifice edge of the valve member, is indicated by the 15 separate sections shown above Figs. 6 and 7. This improved construction effects the variable feed of the carbid at all points with relation to the area or segmental curvature of the recess, and thus effectively insures the most desirable and uniform conditions of 20 operation and generation of gas in this class of lamps, which conditions are attained by the feeding of carbid to the generating chamber in just such quantity as is sufficient to meet the rate of consumption, by the continuous generation of only sufficient gas to 25 maintain the normal degree of pressure. In this respect my invention is distinguished from those feed constructions which are designed to feed the carbid in predetermined graduated quantities, and which therefore 30 do not attain the desired conditions of continuously uniform generation and the maintenance of a normal uniform degree of pressure.

40 The conditions of operation, attained by the improved recessed construction as above set forth, are further enhanced by the features of relative construction and capacity in which the vertical central transverse plane of the plunger intersects the vertex of the segment or point of greatest depth of the continuous segmental curvature of the one-sided open recess.

45 In practice, the length and general dimensions of the segmental concave recess 16 are accurately proportioned to the diameter of the plunger and to the degree of gas generation desired to maintain a uniform pressure in the particular size and type of lamp to 50 which my improvements are applied, the regulation being such that the quantity of carbid fed to the generating chamber will be simply sufficient to effect the generation of sufficient gas to maintain a normal uniform degree of pressure.

55 It will be noted that the construction is such that a guiding action and frictional bearing of the plunger in the valve ring at the feed portion is maintained, by reason 60 of the fact that approximately half of the circumferential surface of the plunger exists

at the side opposite from the concaved recess 16.

It will also be understood that, while the plunger has a frictional action at the orifice edge 8 of the valve ring and is guided thereby, the conditions of operation are such that the generated gas passes from the generating chamber to the carbid holder through said orifice. 70

In relation to the operation just stated 75 and the provision of a guide surface approximating half of the circumferential surface of the plunger, the preferred construction, as herein shown, in which the one-sided open recess is formed in the circumferential 80 surface of the cylindrical plunger rod at one side thereof, has the edges of the single base wall or side of the recess terminating at the line of the cylindrical circumference of the plunger, it being unnecessary in this improved construction to provide an open space at the circumference of the plunger and supplementary to the recess construction for the passage of the generated gas 85 from the generating chamber to the carbid 90 holder. 95

The operative action of the segmental concaved recess 16, which constitutes the feed portion of the plunger, in relation to the orifice edge 8 of the valve ring, is illustrated in Figs. 6 to 8. When the gas pressure lessens and the plunger consequently moves downwardly, its movement a slight distance, for instance to the position shown in Fig. 6, will result in the feed of a small quantity of carbid at the lower portion of the recess through a narrow opening formed at the beginning of the concaved curvature of the recess, which will be a sufficient quantity to immediately restore the gas pressure to its normal uniform degree. But if the degree of pressure has lessened to a greater extent and the plunger reaches a lower point, for instance as shown in Fig. 7, a 100 greater quantity of carbid will be fed by reason of the increased size of the opening 105 which will then follow from the concaved curvature of the recess, and the gas pressure will be at once restored to its normal uniform degree. 110

In like manner, if the pressure has lessened to an extent which causes the plunger to reach a still lower point, for instance as shown in Fig. 8, the feed opening will be of still larger area and a correspondingly greater quantity of carbid will be fed to at once restore the normal uniform degree of pressure. The point indicated in Fig. 8 is the point of greatest depth of the concaved curvature of the recess 115 120 125 130 135 140 145 150 155 160 165 170 175 180 185 190 195 200 205 210 215 220 225 230 235 conditions are sustained in a virtually continuous action at the initial position such as is indicated in Fig. 6, whereby there is virtually a constant feed and generation to just the extent which will so control the conflux of gas-generating elements that the rate of generation will be automatically maintained in uniformity with the rate of consumption.

It will be noted that any conditions of operation which resulted in the movement of the plunger downwardly beyond the position shown in Fig. 8, which is at the central point of the concaved curvature of the recess 16 and therefore at the point of greatest depth of the recess, would result in a lessened feed of carbid as the plunger continued its downward movement, by reason of the fact that the feed opening would gradually decrease in size toward the top of the recess, until the orifice in the valve ring was closed by the cylindrical portion 18 of the plunger immediately above the recess.

Under the general conditions of operation as illustrated in Figs. 6 to 8, the concaved curvature of the recess 16 results in the reception by the recess of a body of feed carbid from the main body in the carbid holder, which is ready for feeding at the opening existing at the lower portion of the concaved curvature of the recess, so that a ready feed of the carbid to the extent of the capacity of said opening is effected. The body of carbid within the recess above the feed opening will be fed downwardly by the action of the upper wall of the recess, and this feeding action of the recess exerts just the required limited degree of pressure by reason of the fact that the continuous curved contour of the recess does not offer defined or positive resistance to the carbid but acts smoothly and uniformly in the exertion of pressure thereon.

It will be noted that, under the improved features of construction as herein set forth, in the actual usual conditions of operation the feed recess has a larger opening for the inlet of carbid thereto, and a larger capacity, at its upper portion, than at the lower or bottom portion at which exists the outlet opening for the deposit of the carbid, which relative conditions result in the effective feed of the carbid under the required pressures and in the required quantity to restore the gas pressure to its normal uniform degree and maintain the rate of generation in uniformity with the rate of consumption.

The leading feature of my invention and improvements is that, owing to the relationship between the recess 16 and the orifice edge of the valve ring and the contour of said recess as hereinbefore fully described, the feed opening afforded by said recess in conjunction with the orifice edge of the

valve ring gradually varies in size as the plunger moves. Thus, in the downward movement of the plunger, the feed opening will gradually increase in size until the point of greatest depth of the concave or curvature of the recess is opposite the orifice edge of the valve ring. Such gradual variation in the size of the feed opening results in the control of the feed of carbid variably so that only a sufficient quantity will be fed to restore the normal degree of gas pressure, and this is an important feature in the operation whereby uniformity of pressure is maintained and the rate of generation is adjusted to uniformity with the rate of consumption.

The construction of the feed portion of the plunger is not only extremely simple and capable of convenient and inexpensive manufacture, but it precludes liability to clogging, or the adhering of slaked carbid to or in the recess 16, as the feed action of the carbid is continuous with relation to the full extent of the recess and the surface thereof is kept clear under the action of the carbid in its downward passage. The construction also enables rapid and convenient cleaning, whenever desired or required, as the entire surface of the recess 16 is exposed and extends in a continuous curvature without intervening partitions or cavities, and is open at both sides, and therefore a suitable brush or cleaning instrument can be passed directly over the entire surface.

I do not desire to be understood as limiting myself to the detail construction and arrangement of parts as herein shown and described, as it is manifest that variations and modifications therein may be resorted to, in the adaptation of my invention to varying conditions of use, without departing from the spirit and scope of my invention and improvements. I therefore reserve the right to all such variations and modifications as properly fall within the scope of my invention and the terms of the following claims.

Having thus described my invention, I claim and desire to secure by Letters Patent:

1. In carbid-feed mechanisms, comprising a carbid holder and a generating chamber in communication by a feed passage and a plunger governing the feed of carbid to water and having at said passage a valve member provided with a projecting edge constituting a feed orifice within which said plunger fits and reciprocates by action of means responsive to pressure of the generated gas, a feed plunger having its feed portion constituted by a one-sided recess extending in the line of the movement of the plunger and formed in the side thereof, the width of the feed-orifice edge of said valve member being a relatively small

percentage of the longitudinal extent of said recess, substantially as and for the purpose set forth.

2. In carbid-feed mechanisms comprising a carbid holder and a generating chamber in communication by a feed passage and a plunger governing the feed of carbid to water and having at said passage a valve member provided with a projecting edge 5 constituting a feed orifice within which said plunger fits and reciprocates by action of means responsive to pressure of the generated gas, a feed plunger having its feed portion constituted by a recess formed in 10 the side of the plunger and gradually increasing in width and depth from its lowermost point, the width of the feed-orifice edge of said valve member being a relatively small percentage of the longitudinal 15 extent of said recess, whereby the feed opening between the base wall of said recess and the orifice edge of said valve member gradually increases and diminishes in both width and depth under the reciprocal 20 action of the plunger.

3. In carbid-feed mechanisms comprising a carbid holder and a generating chamber in communication by a feed passage and a cylindrical feed plunger governing the feed 30 of carbid to water and having at said passage a valve member provided with a projecting edge constituting a circular feed orifice within which said plunger fits and reciprocates by action of means responsive 35 to pressure of the generated gas, a cylindrical feed plunger having its feed portion constituted by a recess extending in the line of movement of the plunger and formed in the side thereof and entirely open at both 40 its sides and at its front and having its base

wall segmentally curved, the width of the feed-orifice edge of said valve member being a relatively small percentage of the longitudinal extent of said recess, whereby the feed opening between the segmental 45 base wall of said recess and the orifice edge of said valve member gradually increases and diminishes in both width and depth under the reciprocal action of the plunger.

4. In the carbid-feed mechanisms comprising a carbid holder and a generating chamber in communication by a feed passage and a plunger governing the feed of carbid to water and having at said passage a valve member provided with a projecting edge 50 constituting a feed orifice within which said plunger fits and reciprocates, a feed plunger having at its feed portion a reduced circumference so related to the orifice edge of said valve member that the 55 opening between said reduced circumference and said orifice edge gradually increases and decreases in both width and depth under the reciprocal movement of the plunger to bring the variable width 60 and depth of the reduced portion of its circumference in relation to said orifice edge, whereby the carbid will be fed in variable 65 quantities for the continuous generation of only sufficient gas to meet the rate of consumption and maintain the normal degree 70 of pressure.

In witness whereof I have signed my name in the presence of the subscribing witnesses.

LOUIS HARTMANN.
